UNITED STATES PATENT OFFICE.

GEORGE W. PIGGOTT, OF NEW YORK, N. Y., ASSIGNOR TO HARTFORD CARPET COMPANY, OF HARTFORD, CONNECTICUT.

DESIGN FOR CARPET.

SPECIFICATION forming part of Design No. 11,851, dated July 6, 1880.

Application filed February 12, 1880. Term of patent 31 years.

To all whom it may concern:

Be it known that I, GEORGE W. PIGGOTT, of the city, county, and State of New York, have invented a new and original Design for Carpets, (Case A,) of which the following is a specification.

This invention relates to a new and original design for carpets, oil-cloths, and similar fabrics.

It consists in the novel grouping and configuration of figures, hereinafter more fully described.

The accompanying photograph illustrates a face view of a carpet having my new design.

A is a central L-shaped figure with its ground strewn with flowers, leaves, and vines. The longer side of figure A is formed of a border, B, composed of parallel ornamented stripes, a. b is a zigzag ornamented stripe, forming the border for a part of the top and shorter sides 20 of figure A and for the bottom of the figure C.

C is a rectangular figure with a flowered ground. Said figure is partially inclosed by the figure A. Two sides of figure C are formed by the border stripe b. Its upper side is formed 25 by the ornamented stripe d, and the end is formed of the vertical elongated ornamented stripe e.

f g are ornamented stripes parallel to stripe e. Between stripes f g is a rectangular field, 30 D, with a spray of flowers overlying it.

E is a border, forming the lower side of the figure A.

G is an angular border adjoining the stripe E, and partially inclosing a field, H, above 35 which is an obliquely-placed border or stripe, I. The lower outer angle of the figure A is overlaid by a rectangular figure, K, placed obliquely with relation to the figure A. This figure K has a richly-ornamented border at 40 the upper sides and a downwardly-projecting extension next to the stripe E'. Flowers cover the body of said figure K.

L is a rectangular figure bordered on two sides by the borders b d, and the other sides 45 are formed by borders h i. On the ground of figure L is laid a spray of flowers, j.

M is a square figure with a bud and leaves on its ground.

N is a zigzag border partly inclosing a field, 50 O, and on the opposite side of said field is a

border, l. The field O is ornamented with a vine and flowers and leaves.

P is a field bordered by the borders or stripes h, d, and m. The ground of field P is overlaid with leaves and flowers and vines.

T is a field inclosed by borders E and G. In field T is a group of flowers and leaves, p, partially lying over borders E G. q is a group of leaves partially overlying the border B and the ground of figure A. r is a group of flowers partially overlying the border B.

U is a group of flowers and leaves partially overlying the field O and its borders.

V is a triangular figure, inclosed by the rectangular figure K and the borders m. On 65 the ground of figure V are flowers and leaves.

I claim—

1. The design for a carpet, consisting of the L-shaped figure A, substantially as herein shown.

2. The design for a carpet, consisting of the L-shaped figure A and the border B, substantially as shown.

3. The design for a carpet, consisting of the L-shaped figure A and border E, substantially 75 as shown.

4. The design for a carpet, consisting of the L-shaped figure A and borders B b E, substantially as shown.

5. The design for a carpet, consisting of the figures A C and intervening border b, substantially as shown.

6. The design for a carpet, consisting of the field D and stripes f g, substantially as shown.

7. The design for a carpet, consisting of the field D, stripes and borders b d e f g E, and figures A and C, substantially as shown.

8. The design for a carpet, consisting of the zigzag border G and border E, substantially 90 as shown.

9. The design for a carpet, consisting of the field H, angular border G, and oblique stripe or border I, substantially as shown.

10. The design for a carpet, consisting of the figure L and borders b d h i, substantially as 95 shown.

11. The design for a carpet, consisting of the square figure M and borders b, i, and N, substantially as shown.

12. The design for a carpet, consisting of the 100

- zigzag border N and field O, substantially as shown.
13. The design for a carpet, consisting of the zigzag border N, field O, and border l, substantially as shown.
14. The design for a carpet, consisting of the field P and borders d h m, substantially as shown.
15. The design for a carpet, consisting of the field T and borders G i o E, substantially as shown.
16. The design for a carpet, consisting of the floral group U, field O, and borders N, o, and l, substantially as shown.
17. The design for a carpet, consisting of the group of leaves q and figure A, and border B, substantially as shown.
18. The design for a carpet, consisting of the triangular figure V and figure K, substantially as shown.
19. The design for a carpet, consisting of the group of flowers r', field H, and border B, substantially as shown.
